(57) **CLAIM**

The ornamental design for a control for suturing device, as shown and described.

DESCRIPTION

FIG. 1 is a perspective view of a control for suturing device in accordance with the present invention; FIG. 2 is a side view of the control for suturing device of FIG. 1;

FIG. 3 is a side view of the opposite side of the control for suturing device of FIGS. 1 and 2;

FIG. 4 is a top view of the control for suturing device of FIGS. 1-3;

FIG. 5 is a bottom view of the control for suturing device of FIGS. 1-4;

FIG. 6 is a front view of the control for suturing device of FIGS. 1-5; and,

FIG. 7 is a back view of the control for suturing device of FIGS. 1-6.

The broken lines are directed to environmental structure and unclaimed subject matter and are for illustrative purposes only; the broken lines form no part of the claimed design.
